UNITED STATES PATENT OFFICE.

BURTON G. SEWELL, OF COLFAX, IOWA.

GATE-OPERATING MEANS.

1,165,544.

Specification of Letters Patent. Patented Dec. 28, 1915.

Application filed February 23, 1915. Serial No. 10,135.

To all whom it may concern:

Be it known that I, BURTON G. SEWELL, a citizen of the United States, and resident of Colfax, in the county of Jasper and State of Iowa, have invented a certain new and useful Gate-Operating Means, of which the following is a specification.

The object of my invention is to provide a gate operating means for controlling a gate from a distance, having parts of simple, durable and inexpensive construction.

A further object is to provide such a gate controlling means having parts so arranged and constructed that the gate will automatically latch or lock in its opened or closed positions, and also so arranged that when power is exerted for opening the gate the free end of the gate is slightly raised for releasing it from the latch device on the adjacent post.

Still a further object is to provide such a gate controlling means, so arranged and constructed that after each operation the controlling mechanism on each side of the gate moves to position for properly operating the gate from either side.

Still a further object of my invention is to provide such a device in which the controlling mechanism may be readily and easily adjusted, making it possible to open or close the gate from positions at different distances from the hinged end of the gate, whereby practically the same mechanism may be used for gates of different lengths.

My invention consists in the construction, combination and arrangement of the various parts of the device, whereby the objects contemplated are attained, as hereinafter more fully set forth, pointed out in my claims and illustrated in the accompanying drawings, in which:

Figure 1 shows a front elevation of a gate and controlling mechanism embodying my invention, the gate being shown in its open position. Fig. 2 shows a top or plan view of the same. Fig. 3 shows a horizontal, sectional view, taken on the line 3—3 of Fig. 1. Fig. 4 shows a similar view, the gate being shown in its closed position, and Fig. 5 shows a plan view of a slightly modified form of the plate forming a part of my device.

It is well-known that in a great many of the gates which may be opened from a distance, there is a large amount of heavy, complicated and expensive mechanism em-

ployed to control the gate. It is my particular purpose, as hereinbefore mentioned, to provide a mechanism which is very inexpensive for the reason that it is simple to make, and may be manufactured with a minimum number of parts.

In the exemplification of my invention, illustrated in the accompanying drawings, I have used the reference numeral 10 to indicate the post at the end of the gate, which is spaced from the post 11 at the free end of the gate. The gate 12 may be hinged to the post 11 in any suitable way. As shown in the accompanying drawings, vertical, spaced, parallel eye bolts 13 are mounted in the post 10, as shown in Fig. 1. The hinged end of the gate is provided with suitable, vertically aligned bearings 14 designed to rest above the respective eye bolts 13, with the openings in the bearings 14 in alignment with each other and with the eyes of the eye bolts 13. Extended through said openings and eyes is an upright rod 15. The openings hereinbefore referred to are of such size as to allow some play of the rod 15 in the bearings, so that the gate may not only swing horizontally, but it may also be tilted slightly upwardly at its forward end.

Along the roadway, spaced from the post 10, is a similar post 16. The posts 10 and 16 are preferably considerably higher above the ground than ordinary fence posts, and may be connected by a suitable brace 17.

Pivoted to the free end of the gate is a vertical swinging latch member 18, the downward movement of which is limited by the pin 19 which serves as a stop.

Secured to the posts 16 and 11 are suitable keepers 20, adapted to receive and engage the latch plate 18.

Rotatably mounted on the side of the post 10 adjacent to the post 16 is an upright rod or shaft 21, the lower end 22 of which is extended substantially parallel with the gate when the latter is closed. A link 23 is pivoted at one end to the end of the extension 22, and at the other end to the gate 12 at a point between the hinged points of the gate and the free end thereof.

Fixed at the upper end of the rod or shaft 21 is a plate 24, which may be substantially rectangular in outline and is preferably longer than it is wide. When the gate is in its closed position, as shown by the dotted lines in Fig. 2, the plate 24 stands in the position shown by the dotted lines in said fig-

ure. The plate 24 is provided with two slots 25 and 26, which may be straight, as shown in Fig. 5, or curved on the arcs of circles whose centers lie in a line with the transverse middle line of the plate 24 in a horizontal plane, as shown in Fig. 2.

At each end of each slot 25 and 26 is a short slot 27 extended toward the nearest side edge of the plate 24. These short slots 10 form pockets the purpose of which will be hereinafter made clear.

Mounted on the post 10 is a substantially horizontal arm 29, extending parallel with the roadway, and a similarly oppositely extending arm 30 mounted on the post 16. Pivoted to the arms 29 and 30 respectively are levers comprising portions 31 extending away from the post 10 from the pivotal points of said levers, and portions 32 extending generally toward the post 10 and inclined upwardly from the pivotal points of said levers. On the upper ends of the portions 32 are downwardly extending portions carrying weights 33. A link 34 is pivoted 15 to the right hand member 32, and is provided at one end with a downward extension 35 received in the slot 26. A two part link 36 is pivoted to the left hand member 32, and is provided with a downwardly extending member 35 received in the slot 25. The link 36 is composed of two parts secured together by yokes 37 and plates 38. Any suitable means may be used for connecting the two parts of the link 36 in such 20 a manner that they may be quickly and easily disconnected for varying the total length of said link, whereby my improved gate controlling mechanism may be easily and quickly adjusted for use with gates 12 of different lengths.

Pivoted to the outer ends of the members 31 are downwardly hanging controlling handles 39.

In the practical operation of my improved gate, assuming that the gate is in its open position, as shown in Fig. 2, then the extension 35 on the member 34 will be in the pocket 27 at the left hand end of the slot 26, and the extension 35 of the left hand link 36 will be received within the right hand pocket 27 of the left hand slot 25. If it is then desired to close the gate, either of the handles 39 may be grasped and drawn downwardly. The operation of the parts is practically the same regardless of which member 31 is moved. Assuming for the sake of illustration, that the left hand member 39 is drawn downwardly, then the plate 24 will be swung from its position shown by the full lines in Fig. 2, to its position shown by the dotted lines in said figure, thereby rotating the rod or shaft 21, and through the link 23 and arm 22 swinging the gate to its closed position. It should be noted in this connection 45 that the extension 22 and the link 23 are of

such lengths that when the gate is in its open position, as illustrated in Fig. 3, the rotation of the rod 21 tends to push the upper hinged end of the gate toward the post 10, and thereby to raise the free end of the gate for 70 releasing the latch members. The parts 22 and 23 just described are also so constructed than when the gate is in its open position, as shown in Fig. 3, the rotation of the rod 21 tends to pull the upper portion of the gate 75 toward the post 10, and thereby to raise the free end of the gate.

Referring again to the illustration of the operation of the gate, it should be noted that as soon as the gate swings to closed position, 80 with the plate 24 shown in its position illustrated by dotted lines in Fig. 2, the extension 35 of the left hand link 36 will pass out of the pocket in which it stood during the swinging movement of the gate and will 85 be moved by the weight 33 in the slot 25 to the opposite pocket 27. The other extension 35 will also be impelled by the other weight 33 until it slides to the opposite end of the slot 26 from that in which it stood 90 when the gate was open. The parts are thus automatically moved to position for again operating the gate from either side thereof.

In Fig. 5 I have shown a slightly modified form of the plate which I have indicated by 95 the reference character 24^a provided with parallel slots 25^a and 26^a which are substantially straight except at their ends where they are curved as illustrated, and terminate 100 in the pockets 27^a.

It will be understood that some changes may be made in the construction and arrangement of the parts of my device, without departing from its essential features, and it is my intent to cover by this application any such changes which may be included within the scope of my claims.

I claim as my invention:

1. In a device of the class described, a post, a gate hinged thereto to swing horizontally, a shaft rotatably mounted adjacent to the hinged end of said gate, means for operatively connecting said shaft and said gate for swinging the gate when the shaft is rotated, a plate on said shaft provided with 110 curved slots having offset pockets at their ends, supports, levers mounted thereon having extensions inclined away from the levers at obtuse angles and toward the said post, weights on said extensions, links pivoted to 115 the respective extensions, said links having downward extensions received in the respective slots, said parts being so arranged that when one of said levers is moved to raise one of said extensions and draw it away from 120 the post, the downward extension on the link secured to the member raised will engage the plate in one of the pockets and move it, thereby rotating the shaft, said parts being 125 also so arranged that when the gate is swung 130

from open to closed position or vice versa, said weights will cause said upward extensions to drop downwardly, thereby moving said links for carrying the extensions thereon to the pockets at the opposite ends of said slots.

2. In a device of the class described, a post, a gate hinged thereto, a shaft rotatably mounted adjacent to the hinged end of said gate, means for operatively connecting said shaft and said gate for swinging the gate when the shaft is rotated, supports, levers mounted on the respective supports, having extensions inclined away from the levers at obtuse angles and toward said post, weights on said extensions, links pivoted to said ex-

tensions, and means for operatively connecting said links with said shaft whereby when the gate is in either its open or its closed position either of said levers may be moved 20 for raising the extension thereof for moving the gate to its other position, said means being so constructed that after the gate has been thus moved, the weights will move said links to proper positions for permitting the 25 gate to be again operated from either lever.

Des Moines, Iowa, January 8, 1915.

BURTON G. SEWELL.
